UNITED STATES PATENT OFFICE.

SUSIE B. SOWDEN, OF PLAINFIELD, NEW JERSEY.

SKIRT-PROTECTOR.

SPECIFICATION forming part of Letters Patent No. 662,246, dated November 20, 1900.

Application filed November 22, 1899. Serial No. 737,974. (No model.)

To all whom it may concern:

Be it known that I, SUSIE B. SOWDEN, a citizen of the United States, residing at Plainfield, Union county, State of New Jersey, have 5 invented a new and useful Improvement in Skirt-Protectors, of which the following is a specification.

My invention consists, primarily, of an improved construction of the skirt-protector, 10 which is made of waterproof material and comprises a detachable facing for forming a pocket-like receptacle for receiving the dress to be protected and that is provided with a series of supporting devices that are adjustable and that are adapted to be removably secured to an underskirt as ordinarily worn, substantially as hereinafter set forth.

My invention further consists in certain combinations and subcombinations to be hereinafter described.

In the accompanying drawings, Figure 1 represents a perspective view of a skirt-protector embodying my invention in a manner to disclose the use of the same. Fig. 2 represents an enlarged view of the construction of the device, and Figs. 3 and 4 show details.

Referring to the drawings, A represents the waterproof skirt, which is to be worn during storms outside of the dress B to be protected 30 and the supporting underskirt C. The detachable facing F is shown secured to the outer skirt A by glove-fastening devices to make a close-fitting joint, and the said facing F is then looped up to receive the skirt B to be protected and the underskirt C and is then secured to the last-named skirt by means of 35 the tape S, which is attached to the hook H, the said hook H being fastened to the underskirt C by a safety-pin, the said hook H and safety-pin P being shown in detail in Fig. 4.

The tape S (shown enlarged in Fig. 3) is formed by the folding of the said tape S upon itself and securing the folds by stitching the same, as shown at x x', at which last-named 45 point the tape is secured to the edge of the facing F, and a loose end is secured to the facing F at the point where the buckle b is held and after the said tape has been passed through the cross-strap c. The free end of 50 the tape S is passed through the hole h in the

facing F and is then adapted to be adjustably fastened into the buckle b. The loop thus formed by the tape S is to be placed in the hook H for supporting the facing F and the included skirt that is to be protected.

As already stated, the hook H is attached to an ordinary underskirt C by the safety-pin P, and then the tape S is adapted to be removed from the hook H by unbuckling the 60 said tape at b and without unfastening the hooks from the underskirt C or reaching under the garments, but by merely lifting the edge of the facing F to unbuckle tape S, an advantage that is of practical consequence.

The free end of the tape S is readily passed 65 through the hole h to be secured to the buckle b, and by the folding of the tape S as described desired limits are provided for the movements of said tape S, which are of advantage.

The form of the hook H is such that the liability of accidental unfastening of the tapes is avoided, and the means for securing the hook H to the underskirt C is of well-known construction and can be done without acquiring skill therefor and can be done to suit the 70 wearer by slight changes in the location of the hooks.

By securing the hooks to an ordinary underskirt the providing of special devices for 80 supporting the protecting-facing is done away with and all the elements are simplified and are made more desirable in their operation, the adjustment being made both by the location of the hooks and by the adjustment 85 of the tapes, for there are a series of hooks H and a series of the tapes S, the said hooks and tapes being placed at suitable intervals, as will be readily understood.

The outer skirt of waterproof material is 90 preferably adapted to be opened at the side and is normally closed by glove-fastening devices or buttons which make a close-fitting seam and that render the skirt easy to put on and to remove.

The facing F is secured to the outer skirt by the glove-fastening devices placed at intervals and is made to set smooth along the inner surface of the protecting-skirt A.

What I claim is—

55

70

75

95

100

As an article of manufacture a protecting-skirt open at the side and provided with a removably-attached facing secured thereto by glove-fastening devices and adapted to be secured to an inner garment by looped tabs that are adjustably attached at one end to said facing and permanently attached at the

other end to said facing, substantially as shown and described.

SUSIE B. SOWDEN.
